UNITED STATES PATENT OFFICE.

HERBERT HUNT, HERBERT WILLIAM HUNT, AND PERCY HUNT, OF MANCHESTER,
ENGLAND.

TWIST-DRILL-POINT-GRINDING MACHINE.

Application filed June 4, 1920. Serial No. 386,589.

To all whom it may concern:

Be it known that we, HERBERT HUNT, HERBERT WILLIAM HUNT, and PERCY HUNT, subjects of the King of Great Britain and Ireland, and residents of Manchester, England, have invented certain new and useful Improvements in Twist-Drill-Point-Grinding Machines (for which we have filed an application in Great Britain and Ireland, No. 4213, dated Mar. 11, 1918), of which the following is a specification.

This invention has for its objects (1) a construction of machine which will ensure the accurate pointing of a twist drill, and (2) a machine which will ensure of the cutting edges of the point of the drill having an uniform angle of clearance from apex to circumference of the drill point.

In achieving the first object of the invention, the drill, whilst its point is being acted upon by the grinding wheel, is supported circumferentially near the said point in a close but free fitting bush or sleeve which serves to centre the drill and act as a steady for the drill to bear against whilst the point is being ground. The said bush or sleeve by having a portion of its end cut away to form a shoulder also serves in conjunction with one of the flutes of the drill, to facilitate the correct setting of the drill in relation to the drill holding spindle.

In achieving the second object of the invention, the drill in addition to having a rotary movement about its own longitudinal axis, and a slight longitudinal movement towards and away from the grinding wheel during each half rotation of the drill, has an angular movement about a vertical axis near to the end to be pointed, the said vertical axis preferably passing through the said sleeve, and the combined movements resulting (a) in the drill being accurately pointed and the cutting edges ground, and (b) in the clearance behind the cutting edges being the same or almost the same angle near the apex of the drill point as at the periphery, thereby rendering those parts of each cutting edge near the apex as efficient, or almost as efficient as the parts near the periphery of the drill point.

A further feature of the invention consists in obtaining the said forward movement of the drill twice in each revolution

of the drill by a single cam, or in other words, using one cam for both lips of the 55 drill point.

Another feature consists in using the periphery of the grinding wheel (instead of one of its side faces) for grinding the drill point, and in moving the wheel laterally 60 during the grinding operation so as to keep the periphery of the wheel true and flat. A further feature of the invention consists in providing means for varying the lateral movement of the grinding wheel, and moving the wheel clear of the drill point when requiring to change the drill. Alternatively, the invention consists in moving the drill bodily to and fro across the edge of the grinding wheel, the latter in such case 70 being capable of rotary movement only. Combined with the improved machine may be an attachment for grinding the flutes of the drill.

In order that the invention shall be more 75 readily understood reference will now be made to the accompanying drawings, whereon:

Fig. 1 illustrates a front elevation (in part).

Fig. 2 a left hand elevation (in part) and

Fig. 3 a plan (in part) of the improved machine.

Figs. 4 and 5 illustrate side and end views respectively of the bush for supporting the 85 drill near to the end to be ground.

Fig. 6 illustrates a form of cam used in the machine.

Figs. 7 to 13 illustrate various further detailed parts hereinafter described.

Fig. 14 illustrates a modified arrangement of belt driving pulley and clutch.

Fig. 15 illustrates a front view.

Fig. 16 a plan, and

Fig. 17 an end view of a modified construction of the improved machine. In Figs. 1 and 15 the drill holding mechanism is shown at right angles to the axis of the grinding wheel.

Fig. 18 illustrates a plan view of a modification of Figs. 15, 16 and 17.

Figs. 19 and 20 are side and plan views respectively of an attachment used with the improved machine.

Referring to Figs. 1 to 14, the machine 105 comprises a pedestal 1 upon which rests

a hollow stand 2 and tray 3. In one with said tray is a raised guide block 4 whereon is mounted a slide 5, see Figs. 7 and 8, capable of moving to and fro along the guide block 4. Upon said slide rests a plate 6, see Figs. 9, 10 and 11. Both slide and plate are provided with a hole through which passes a stud 7, see Fig. 3. The stud loosely fits the hole in the slide, but is held firmly in the hole of the plate, so as to turn therewith by a set screw 7^c.

In one with said plate 6 is a guard 6^a, concentric to the stud 7. In the parallel sided part of the plate is a parallel sided sinking, see Fig. 10, the edges 6^b, 6^b of which are bevelled, see Fig. 11, to form guides for a drill head 8. The slide 5 extends below the drill head 8 and in the part below the drill head is formed with a curved slot 9, see Figs. 3 and 7. Extending downwards from the plate and passing loosely through the slot 9 in slide 5 are roller-carrying studs 10 whereby the plate 6, whilst free to move radially about the stud 7 is held to the slide 5 and guided in the path of the slot. In the drill head 8 is mounted the spindle 11, the forward end of the spindle being hollow and fitted with the usual chuck 12 for receiving and centrally gripping the twist drill requiring to be ground.

In one with the drill head 8 is a boss 15, see Fig. 2, which forms the bearing of a spindle 14. Upon the upper end of the spindle is keyed a bevel pinion 15 and a disc cam 16, see Fig. 6. Keyed upon the rear end of the drill-holding spindle 11 is a further bevel wheel 17, this latter being double the size of, and meshing with the pinion 15. Upon the lower end of the spindle 14 is keyed a bevel wheel 18.

By means of a pair of plungers 19, 19 and springs 20, 20 arranged within holes in the base of the drill head, see Figs. 1, 3 and 13, a hardened steel stud 21 on a cross-bar 6^c on plate 6 is constantly held in yielding contact with the periphery of the disc cam.

Upon or in one with the stud 7 are clamping jaws 7^e, in which fits a bush 7^b, a screw 7^e clamping the bush when set to the correct position. The drill to be ground projects through the bush, see Fig. 4. The bush at its forward end is partly cut away to form shoulders 7^d, see Figs. 4 and 5, said shoulders lying about a sixteenth of the interior diameter of the bush or sleeve above the longitudinal axis of the sleeve. By means of one of the shoulders, and by causing one edge of a flute in the drill to lie flush with the shoulder (the fingers readily feeling when this is done), the drill can be readily set to the correct position relatively to the spindle 11, see Fig. 5. The internal diameter of the bush or sleeve is such as to closely but loosely fit the drill to be pointed. With each machine will be supplied a set of in-

terchangeable bushes or sleeves, the internal diameters of which will vary with the different diameters of drills to be pointed.

Extending from the boss 13 is an arm 13^a which terminates in a tubular part 13^b. In such part rotatably fits one end of the shaft 22. Upon the said shaft is keyed a bevel pinion 23 which meshes with the bevel wheel 18. Also upon the shaft 22, but at the other side of the tubular part 13^b is keyed a collar 24, whereby, with any lateral movement of the boss and arm, the shaft 22 is moved endwise. Eccentrically connected at one end to the bevel wheel 18 is a link 25, the other end of which is pivotally connected to an arm 26 branching from the slide 5, see Figs. 1, 3 and 7. With the wheel 18 in motion, the plate 6 is moved to and fro about the pivot 7.

Secured to and extending from the underside of the tray 3 is a bracket 27, which at its free end supports the bearings 28 of the fast and loose belt pulleys 29, 30, said bearings being held to the bracket by a plain stud 31, and set screw 32, and being free to swivel in a horizontal plane about said stud.

The shaft 22 is free to slide to and fro within the pulley bearings and pulleys, the fast pulley 29 being slidably keyed to the shaft. A belt-fork shifting bar 33 is mounted in the upper ends of the bearings, and a ball and spring (concealed within one of the bearings) and notches in the bar 33 serve to hold the belt forks in either of two positions. In lieu of the fast and loose belt pulleys and belt fork, a single belt pulley 29^a and clutch 29^b, see Fig. 14, may be provided.

At the right-hand end of the machine is arranged the grinding wheel 34. This wheel is carried by a shaft 35 mounted in ball bearings within a slide 36, the ball bearings being preferably of the self-adjusting type, so as to keep the wheel shaft always in alignment. Keyed upon the rear end of the shaft 35 is the belt pulley 37. Below the slide 36 is a stud 38 free to swivel about its axis and connected to such stud is one end of a lever 39. This lever is fulcrumed on a peg 40 fitting a hole in the block 41 cast in one with, or fitted to the tray 3. Pivotedly connected to the lever 39 is a bar 42 having a series of holes 43 by which the bar may engage a pin 44 on the plate 6, the bar terminating in a handle 45 by which it may be lifted clear of the pin 44 or lowered on to such pin.

By means of this bar and lever, the grinding wheel 34, when the plate 6 is swung to and fro about the stud 7 is caused to move to and fro endwise, i. e., in the direction of the arrows*, see Fig. 3.

When requiring to insert a drill in the chuck 12, the bar 42 is lifted off the pin 44, and by pulling the bar forward the wheel 130

34 and bearing 36 are moved to the rear of the machine. A wheel guard 46 is fixed to and moves with the bearing 36.

An opening 3^a in the tray allows the débris from the drill point and wheel to fall into a pen 47 within the stand 2, that part of the plate 6 within the guard 6^a, being sloped so as to direct the lubricant and débris to the opening 3^a. Upon the side 5 of the slide 5 is secured a lug 5^a, see Figs. 3 and 7, which is screw-threaded internally, and through which screws a screwed spindle 48. This spindle is rotatably mounted in a fixed boss 49 and is held 10 against endwise movement by a flange 50 and collar 51. Upon said spindle is keyed a ratchet wheel 52 and secured adjustably to the spindle by nut 48^a is a hand-wheel 53. Pivotally supported on the tray 3 is a lever 20 arm 54, see Fig. 2, which near to its upper end carries a pawl 55, the free end of the pawl being adapted to engage the teeth of the ratchet wheel 52. Upon this side of the lever arm 54 furthest from the ratchet 25 wheel is a projection 54^a, which overlies and under the force of a spring 54^b, bears against the head of a screw 56 screwing into the tray 3. Upon the plate 6, see Fig. 3, is a projection 6^a which comes directly opposite the lever arm 54, and with the 30 pivotal movements of the plate 6 in one direction, serves to push against the lever arm 54 and operate the pawl 55 which, in turn, rotates the ratchet wheel a portion 35 of a revolution. With the ratchet wheel thus rotated, the screw 48 is rotated and thereby caused to bodily traverse the slide 5 and with it plate 6, drill head 8, drill 40 spindle 11 and drill point towards the grinding wheel, the shaft 22 and pulley bearings 28 allowing of this by being free to swivel about the stud 31 and spindle 14.

It will now be seen that with the shaft 22 in motion the drill-holding spindle and drill 45 will be rotated about their own axis. Simultaneously with the said rotary movement of the drill the disc cam 16, during each half-revolution of the drill, will impart to the drill a slight longitudinal movement 50 towards and away from the grinding wheel. Further, owing to the eccentric connection of the link 26 with the bevel wheel 18, the plate 6 and the drill-holding spindle and drill will move to and fro in the arc of a 55 circle, having stud 7 as axis, the combined motions, with the drill point in contact with the grinding wheel and with the axis of the drill lying at an oblique angle to the periphery of the grinding wheel, serving 60 primarily to point the drill, and secondly to grind and impart clearance to the cutting edges of the drill point, the angle of clearance being the same or practically the same near the apex of the drill point as near the 65 periphery. This uniformity of the angle of

clearance is due to giving the drill a pivotal or swinging movement whilst moving it endwise towards the grinding wheel, and also to arranging the vertical axis about which the drill moves pivotally a short distance from the end of the drill. 70

The shape of the disc cam 16 is shown more clearly in Fig. 6. As previously stated, the cam is driven through gears of two to one ratio and therefore the drill is moved to and fro endwise twice in each rotation of the drill. One half rotation of wheel 18 imparts angular movement to the plate 6 in one direction and the other half rotation produces angular motion in the opposite direction. 80 During such rotation the cam rotates once. In the first half rotation of the cam it moves the drill towards the grinding wheel, and allows it to move back during the second half of the rotation. Through the gears 15, 17, the drill, in the same period, makes only half a rotation. 85

To aid in setting the drill relatively to the drill spindle 11, a short latching lever 57 is provided which is pivoted to a lug on the top 90 of the drill head 8 and adapted to engage a notch in the collar 58 adjustably secured to the spindle 11. After setting the drill spindle, the latch is thrown back and the spindle and drill made free to rotate. The drill is 95 then inserted with one of the flute edges level with the shoulder 7^a, as previously described. The lateral movement of the grinding wheel will preferably be not less than the full width of the wheel, so that whilst 100 grinding the drill the wheel will be kept true and flat.

Obviously the bush or sleeve 7^b may be shouldered at both ends and thus be reversible. There will be a set of bushes or sleeves 105 7^b for a range of sizes of drills, and for each range the bushes or sleeves will preferably be the same diameter on their exterior, whilst the interior diameter will vary to suit the drill. For a range of larger or smaller 110 sizes of drills, the stud 7 may be changed for a stud having a larger opening for the bushes, or the hole in the stud may be fitted with a liner, capable of being removed to allow of bushes of larger or smaller diameter being used. 115

The hand-wheel 53 may be furnished with a pin 53^a designed to lift the pawl 55 clear of the teeth of the ratchet wheel after a predetermined rotation of the ratchet wheel and a corresponding predetermined traverse of the slide 5. If desired, the screw 48 may be rotated by hand, and while the screw is being so rotated, the pawl 55 may be turned up out of the way, a spring and plunger 59 120 holding it in the raised position. 125

By altering the lever 39 from one hole to another the endwise movement of the grinding wheel may be varied.

Referring now to Figs. 15 to 20, the ma. 130

chine therein shown is similar to that shown in Figs. 1 to 14, but differs chiefly in that the grinding wheel 34 is incapable of endwise movement and the drill is bodily moved to and fro in a direction parallel with the axis of the grinding wheel.

Other features of difference are the arrangement of mechanism for imparting angular movement to the drill, and the arrangement of cam for imparting endwise movement to the drill.

In this modification the tray 60 carries a guide 61 whereon is mounted a slide 62, this latter being movable along the guide by means of a screw 63 screwing through a screwed part 64 of the guide 61. In one with the slide 62 is the guide 65 of a further slide 66 adapted to move in a direction at right angles to the slide 62. The pivot stud 67 of the plate 68 is carried by the slide 66, and said slide extends rearwardly to support the rearward part of the plate 68, a roller 69 being provided for the extension of the slide to rest upon.

Upon the rear end of the plate 68 is mounted the drill head 70 in which is mounted the hollow drill-holding spindle 71, said spindle being slidably mounted within a tube or bush 72 in the head. Said tube at one end is formed in one with a boss 73 and near such boss carries a plate 74. At its other end the tube is coned and slotted, that part of its periphery adjacent to the conical end being screw-threaded and adapted to receive the screwed part of the boss of the hand wheel 75. By slackening the hand wheel the tube 72 frees the spindle 71 and allows the latter to be adjusted endwise by the knob-ended pin 76 whilst by tightening the hand wheel the tube 72 and the spindle 71 are held in the correct positions relatively to the grinding wheel 34.

At its forward end the twist drill is supported in an interchangeable bush 77 carried by the pivot 67 as in the machine shown in Figs. 1 to 14.

Mounted in the drill head is a lay shaft 78 whereon is slidably keyed a spur pinion 79 and a bevel pinion 80, the former meshing with a spur wheel 81 on the tube 72 and the latter meshing with a bevel wheel 82 keyed to a vertical spindle 83 carried in a bearing bracket rising from the plate 68, see Fig. 16. Upon said vertical spindle 83 is also keyed a larger bevel wheel 84 and with such wheel meshes a bevel wheel 85 keyed to a short spindle 86 carried in a bracket 87 and furnished with a clutch 88 and handle 89, one half the clutch and the handle being movable as one and the other half of the clutch being in one with the boss of the bevel wheel 85.

Meshing with the bevel wheel 84 is a further bevel wheel 90 loosely mounted on a shaft 91, the boss of the wheel fitting a

bearing 92 branching from the bearing bracket of the vertical spindle 83 and being provided with a half-clutch 93 whereby and a complementary half-clutch 94 (slidably keyed on the shaft 91) and a lever 95, see Fig. 16, the motion of the shaft 91 may be transmitted to the bevel wheel 90 or whereby the driving connection may be broken.

The shaft 78 is slidable in the drill head and at one end said shaft is connected to the plate 74 on the tube 72. At its other end the shaft 78 is fitted with a cam 95. Within recesses in the drill head are springs 96 and telescopically fitting the springs and recesses are plunger-headed pins 97 carried by the plate 74. Upon an extension 68^a of the plate 68 is a hardened steel pin 68^b against which the cam 95 bears under the pressure of the springs 96.

Secured to the edge of the extension of the slide 66 is a bracket 98 and connecting the free end of said bracket with an eccentrically arranged pin on the bevel wheel 84 is a link 99. The shaft 91 receives its rotary motion from the main shaft 100 through a worm 101 and worm wheel 102 and also through a bevel wheel 103 mounted on vertical spindle 104, see Fig. 17, and a bevel wheel 105 mounted on the shaft 91.

Under the rotations of the bevel wheel 84 the plate 68 and with it the hollow spindle 71 and the twist drill are given a to-and-fro angular movement about the pivot stud 67, whilst the hollow spindle 71 and twist drill are rotated about their own axes, further by means of the cam 95 and springs 96 the drill is given an endwise movement towards and away from the grinding wheel twice in each revolution of the drill. With the drill held at an oblique angle to the periphery of the grinding wheel and moved as aforesaid, the drill is ground and pointed, the necessary clearance is imparted to the cutting edges of the drill point, and the angle of clearance is practically the same for the whole length of the cutting edges.

Engaging an eccentrically positioned block 106 on the worm wheel 102 is the grooved arm of a bell-crank lever 107 the other arm of such lever being connected by a link 108 to the slide 66. The lever takes its fulcrum on a bracket 109 branching from the end bearing of the main driving shaft. By this arrangement the drill is moved bodily to and fro across the periphery of the grinding wheel, thus ensuring of the wheel wearing evenly.

As in the machine shown in Fig. 1, a latch 110 pivoted to the drill head and adapted to enter a notch in the boss 73 of the tube 72 serves to hold the spindle against rotation whilst the twist drill is being placed in the clutch and also serves to position the drill for grinding.

The setting of the drill spindle 71 to the

correct position for receiving the drill is effected by the handle 89 and clutch 88, the latter being normally held out of engagement by a spring concealed within the clutch 5 but on being engaged serving to rotate the bevel wheels 85, 84 and spur wheels 79, 81. To enable the slide 66 to take up various positions relatively to the guide 65, the link 108 is connected to the slide through 10 medium of a rack 111 mounted in a groove below the slide, and engaging such rack is a toothed wheel mounted upon a vertical spindle 112 journaled in the slide and at its upper end being fitted with a fixed notched 15 wheel 113 and a swivelling lever 114 carrying a spring-pressed locking pin 115, the lever, when the pin is drawn back, allowing of the rotation of the toothed wheel below the slide and the adjustment of the 20 slide along the rack.

Instead of being operated by power, the improved machine shown in Figs. 15 to 17 may be operated by hand, in which case the shaft 91, the bevel wheel 90, clutches 93, 94, 25 bevel wheels 103 and 105, worm wheel 102, and worm 101 will be dispensed with, see Fig. 18. In such connection the lever 107, eccentric block 106, and link 108 are also dispensed with, and the adjustment of the 30 slide 66 is effected periodically by a hand-wheel 116 and screw 117 as shown in Fig. 18, the screw being rotatably mounted in a bracket or boss 66^a on slide 66 and the screw engaging a screwed part 65^a of the guide 65.

35 When the machine is hand-operated, the clutch 88 may be dispensed with, the handle 89 being fixed to the boss of the bevel wheel 85.

The twist drill may be automatically fed 40 against the grinding wheel after each complete revolution, by mechanism similar to that already described.

The flutes of a drill are usually narrower towards the shank end of the drill and as the 45 point of the drill is ground away in sharpening it is desirable that the flutes should be maintained at a uniform width. For this purpose the improved machine comprises a flute grinding wheel 118, see Figs. 17, 19 and 20 mounted upon an extension of the 50 shaft 100. Further the tray 60 is fitted with an adjustable work holder, such holder com-

prising a non-rotary vertical screw 119 passing through a fixed boss 120 with internally screw-threaded bush 121, said bush being furnished with a hand-wheel 122 whereby it may be rotated and the screw 119 raised or lowered. At its upper end the screw carries a rod or bar 123 upon which is adjustably mounted a slide 124. In one with such 55 slide and lying at an angle therewith in plan and elevation is a V-shaped tool carrier 125 the said slide and carrier being movable to and fro on the bar 123 by means of a lever 126 pivoted to the carrier and projecting 60 loosely through an opening in the relatively fixed bar 123, see Fig. 20. The drill is laid in the carrier and positioned with its pointed end next the grinding wheel by means of an 65 adjustable stop block 127.

70 Upon the end of the carrier is a small Z-shaped plate 128, see Fig. 17, adapted to act as the gauge for holding the drill in the correct position for grinding first one flute and then the other, the small spurs being 75 preferably made to two sizes to suit different sizes of drills.

The angle of the carrier 125 relatively to the bar 123 in plan is such as to cause the 80 flutes of the drill to be practically parallel with the grinding wheel 118.

What we claim is:-

In a twist drill point grinding machine, a vertically disposed stud, a support for said stud on which it rests solidly while free to 85 swivel, said stud near its upper end having a through opening and being slotted vertically to form jaws, a cylindrical interchangeable bush within said opening and between said jaws, the ends of the bush which extend 90 beyond the sides of the stud having radiating shoulders each lying a slight distance out of the plane of the longitudinal axis of the bush, the inner diameter of the bush being such as to receive a twist drill and hold 95 same against lateral disturbance in all directions whilst leaving the drill free to rotate, and means for tightening the jaws on to said bush, as herein set forth.

In witness whereof we have hereunto set 100 our hands.

HERBERT HUNT.

PERCY HUNT.

HERBERT WILLIAM HUNT.
